UNITED STATES PATENT OFFICE.

ERNEST S. WILLIAMS, OF TORONTO, ONTARIO, CANADA.

SANITARY SERVING DEVICE.

1,313,364.

Specification of Letters Patent.

Patented Aug. 19, 1919.

Application filed December 16, 1918. Serial No. 267,003.

To all whom it may concern:

Be it known that I, ERNEST S. WILLIAMS, a subject of the King of Great Britain, and resident of the city of Toronto, county of York, Province of Ontario, in the Dominion of Canada, have invented certain new and useful Improvements in Sanitary Serving Devices, described in the following specification and illustrated in the accompanying drawings, that form part of the same.

The principal objects of this invention are to protect the food displayed for sale in restaurants from contamination by the customers passing closely thereto and to devise a serving apparatus facilitating the quick handling of food while maintaining the protection thereof, and also to enable the operation being effected with the use of one hand.

20 The principal feature of the invention consists in the novel construction and arrangement of parts whereby the articles of food are completely covered in upon the front side and are arranged individually and adapted 25 to be withdrawn by the customer without interference with other articles, the individual articles being arranged in separate compartments closed at the front by individually opening doors.

30 A further important feature consists in the novel manner of opening the doors and in effecting their closure upon the removal of the goods.

In the drawings, Figure 1 is a perspective view of a portion of a serving device constructed according to this invention, showing the various positions of the members in the removal of the goods.

Fig. 2 is an underside plan view of a 40 series of serving devices illustrating the various positions of the parts in the removal of the goods.

According to the laws recently enacted respecting the protection of cooked foods in restaurants it has become necessary to protect such materials from contamination and to place all such food stuffs behind a protecting screen, which in places where the food is displayed for sale is of glass. These regulations have rendered the matter of serving the public in cafeterias much more difficult and this invention has been devised to provide the protection required while enabling the customer to serve himself.

55 In the form of the invention herein shown a frame is constructed of front and back up-

rights 1 and 2 which are connected together by plates 3 which may form complete shelves if desired, but are here shown as forming guides for movable shelves, said plates having the grooved strips 4 secured to their longitudinal edges.

Upright flat bars 5 are secured to the inner sides of the front uprights and are bent rearwardly at the top and extend over and are secured to the tops of the rear uprights. The upper portions 6 of the bars 5 extend beyond the rear uprights and are connected together by an angle bar 7.

A corresponding angle bar 8 is secured to the top of the front uprights and a sheet of glass 9 or other suitable material is placed upon said angles and forms a protecting top.

Transverse bars 10 are arranged between the front uprights, their upper surfaces being arranged slightly below the grooved strips 4 and suitable doors 11 are arranged to close the openings thus formed. The doors are here shown arranged in pairs 80 hinged at the sides to the vertical bars and closing centrally and they are formed with glass panels in the upper portion and provided with spaces 12 in the lower front sides to receive indicating cards for names and 85 prices of the goods. The doors are preferably spring held closed.

Sliding shelves 13 are arranged between the plates 3, having laterally extending flanges 14 sliding in the grooved strips 4. 90 The front ends of these shelves are preferably rounded and in the center they are provided with handle projections 15. These projections are arranged to fit snugly against the top surface of the cross bars 10 and are 95 offset downwardly to form a positive stop to limit their inward movement, the outer end projecting so as to be readily grasped between the thumb and finger in order to be withdrawn.

100 The doors close over the handle members 15 and abut the front edges of the shelves, being held in contact therewith by the spring hinges which may be of any suitable form. The structure thus formed provides a series 105 of vertical shelves and any desirable number may be arranged in the stack. These shelves are preferably formed with upwardly extending flanges 16 at the back end and they are open from the rear so that the 110 attendants may place fresh articles thereon, as such are removed from the front side by

customers. One of each pair of doors is provided with a projecting ratchet lug 17, which is adapted to engage a notch 18 formed in the edge of the shelves 13 when the shelf has been withdrawn a certain distance, so that a customer may pull the shelf out until it locks and may then remove the plate or other dish from the shelf.

The doors are held in a position sloping 10 slightly inward when the ratchet lug engages the shelf, so that the distance between the outer edges of the doors is less than the diameter of the plate carried upon the shelf and when the customer removes the plate 15 the edges of the plate engage the doors and swing them farther apart, thereby releasing the ratchet lug from engagement with the shelf.

The shelves are preferably drawn backwardly upon being so released to their original position by means of a suitable spring which is here shown as a flat spring 19 secured to the inner side of the front bar 10 and engaging a lug 20 on the underside of 25 the shelf. When the plate is fully withdrawn from contact with the doors the spring hinges swing the doors back into their closed position.

The inner sides of the doors 11 are provided with inwardly extending flanges 21 arranged at the bottom of the glass panels. These flanges are provided to extend over the edges of the plate while it is being withdrawn, so as to prevent the plate tipping 35 and also to protect the glass in the doors from being scratched by the removal of the plate.

The operation is extremely simple, the customer passing in front of the case determines 40 the article desired and grasping the handle 15 with the thumb and forefinger outside of the upper compartment, the shelf is drawn out and the rounded end of the shelf engaging the inner sides of the doors swings them upon their hinges, until the ratchet lug on the door enters the notch. The handle is then released but the shelf stays out and the plate is then grasped by the customer and withdrawn. As the plate 45 is drawn out it spreads the doors farther apart releasing the shelf which immediately springs back to its original position and upon the final removal of the plate from contact with the doors they swing inwardly 55 to the closed position. The compartment is thus closed immediately upon the removal of the goods and the attendant behind the counter may place a new dish upon the shelf.

60 It will be readily understood that the detail construction of a device such as herein described may be altered very considerably without departing from the spirit of the invention so long as the main feature of providing a structure arranged in separate

compartments having doors closing the fronts of these compartments adapted to be opened by customers for the removal of the goods and closed after the removal, is maintained.

70

What I claim as my invention is:—

1. A sanitary serving device comprising, a frame having a plurality of compartments open at the back, closures closing the fronts of the individual compartments, and means for operating said closures actuated by the removal of an article from the compartment.

75

2. A sanitary serving device comprising, a frame having a plurality of individual compartments, closures arranged at the front of each of said compartments, means for holding said closures open for the removal of the article contained within the compartment, and means for automatically closing said closures upon the removal of the article from the compartment.

80

3. A sanitary serving device comprising, a frame having a plurality of individual compartments open at the front, doors closing the fronts of said compartments, shelves 90 slidably arranged in said frame adapted to be drawn outwardly through the front openings and to open said doors, means for returning said shelves to their normal positions in the frame following the removal of the article carried on the shelf, and means for closing the doors following the return of the shelves to their normal position.

95

4. A sanitary serving device comprising, a frame having a plurality of individual compartments open at the front, spring closing doors closing the fronts of said compartments, a slideable shelf arranged in each of said compartments adapted to be drawn forwardly and to engage and open the doors, means for holding the doors open when the shelf is drawn forwardly, and means for returning the shelf to its normal position actuated by the removal of the article carried upon the shelf.

100

5. A sanitary serving device comprising, a frame having a plurality of individual compartments open at the front, a pair of spring closed doors arranged in the front opening of each compartment, a slideable shelf arranged in each of said compartments and adapted to be drawn forwardly, spring means for returning the shelf to its normal position, means for temporarily locking the shelf in its extended position 115 and the doors in their open position, and means for disengaging said locking means actuated by the removal of the article from the shelf.

110

6. A sanitary serving device comprising, 120 a frame formed of uprights connected in pairs by horizontal members having longitudinal grooves in the side walls, transverse bars connecting the uprights, shelves extending between said horizontal members 130

and sliding in the grooves therein and having rounded forward ends and provided with projecting handles, doors arranged in individual pairs closing the openings to the individual shelves and spring held in contact with the rounded ends of said shelves, a latch member adapted to temporarily lock said shelf in a forwardly extended position and the doors partly open and adapted 10 upon the further opening of the doors to release said shelf, and spring means for returning the shelf to its normal position.

7. A sanitary serving device, comprising, a plurality of front and back uprights arranged in pairs, horizontal shelf guides 15 rigidly connecting the front and back uprights, shelves slidably arranged in said guides, doors arranged between the front uprights adapted to close automatically, and a rigid shelf secured to the top of said uprights and extending over said movable shelves. 20

ERNEST S. WILLIAMS.
